(57) **CLAIM**

The ornamental design for a carton for holding beverage or other containers, as shown and described.

DESCRIPTION

FIG. 1 is a perspective view of a carton for holding beverage or other containers, showing my new design in condition of

use, with a first side compartment cover shown in an open position and an opposite, second side compartment cover shown in a closed position;

FIG. 2 is a perspective view of the carton for holding beverage or other containers thereof;

FIG. 3 is a top plan view of the carton for holding beverage or other containers thereof;

FIG. 4 is a first side elevation view of the carton for holding beverage or other containers thereof;

FIG. 5 is a left end elevation view of the carton for holding beverage or other containers thereof;

FIG. 6 is a right end elevation view of the carton for holding beverage or other containers thereof;

FIG. 7 is a bottom plan view of the carton for holding beverage or other containers thereof;

FIG. 8 is a second side elevation view of the carton for holding beverage or other containers thereof;

FIG. 9 is a second side perspective view of the carton for holding beverage or other containers thereof, shown with the first side compartment cover in a closed position and the opposite, second side compartment cover in an open position; FIG. 10 is a top plan view of the carton for holding beverage or other containers depicted in FIG. 9;

FIG. 11 is a second side elevation view of the carton for holding beverage or other containers depicted in FIG. 9;

FIG. 12 is a right end elevation view of the carton for holding beverage or other containers depicted in FIG. 9;

FIG. 13 is a left end elevation view of the carton for holding beverage or other containers depicted in FIG. 9;

FIG. 14 is a bottom plan view of the carton for holding beverage or other containers depicted in FIG. 9; and,

FIG. 15 is a first side elevation view of the carton for holding beverage or other containers depicted in FIG. 9.

The broken line showing of a central compartment lid and four beverage bottles in FIG. 1 is for illustrative purposes only and forms no part of the claimed design or of a specified embodiment thereof.
